George E. Buckley.

UNITED STATES PATENT OFFICE.

JAMES BOUNDS, OF PHILADELPHIA, PENNSYLVANIA.

IMPROVEMENT IN FIRE-PROOF TILING FOR FLOORS AND CEILINGS.

Specification forming part of Letters Patent No. 128,944, dated July 16, 1872.

To all whom it may concern:

Be it known that I, JAMES BOUNDS, of the city of Philadelphia, State of Pennsylvania, have invented certain new and useful Improvements in Floors or Ceilings for Fire-Proof Buildings; and I do hereby declare the following to be a full, clear, and exact description of the same, reference being had to the annexed drawing making part hereof, in which—

Figure 1 is a perspective view of my improvement; Fig. 2, a vertical longitudinal sectional view on line T W of Fig. 1; Fig. 3, a vertical cross-sectional view on line X Y of Fig. 1.

My invention consists of an improved ventilating, fire-proof, truncated floor and ceiling tile, made of terra-cotta, cement, artificial stone, metals, or other incombustible material, the whole to be made and arranged substantially as shown and set forth in the drawing and in the following description. The tile is open for ventilation, but this feature may be omitted. One of the features of my tile is that it completely covers and protects the beams, joists, or girders.

To enable others skilled in the art to make and use my invention, I will describe its construction and operation.

In the drawing, A is the body of the tile; B, the girder, joist, or beam; (I shall hereafter, in the specification, for the sake of brevity, call it a girder;) C C', bulk-heads or partitions; D, a brace for supporting these partitions, and acts also as a partition itself, as will be hereinafter shown; E E, openings in the sides of the tile; G, an opening in the bottom of the tile; H, the bottom of the tile; I, the top; K K, the sides; L, slots in the ends of the tiles to receive the flanges or edges of the girders. M, Fig. 2, shows the girder completely covered and protected.

I prefer to construct the tile of some fire-proof material, which will not warp or bend or be otherwise injuriously affected on coming in contact with flame or heat; and I will describe the construction of a tile made of terra-cotta, using girders of iron.

The body A of the tile, composed of the sides K K and the top I and bottom H, is formed first, leaving its ends open, and the slots L are cut in the sides a short distance above the bottom, and below the top in the

ends, as shown; these slots are left or cut out to receive the edges of the flanges of a double-T, or an I-shaped girder when such a girder is used, and the sides K do not extend out quite so far by half the thickness of the girder as the top I and bottom H. The girder B is in this manner clasped and completely covered and protected, as shown at M, Fig. 2, when two of the tiles are joined at the ends, as shown.

The tiles are laid after the girders have been put down, but not secured in place; and after all the tiles are slipped into place between the girders, said girders are securely fastened at their ends and another girder being laid down at such a distance from its fellow girder as will leave space sufficiently wide to receive a tile; the rest of the tiles are then slipped into place. In inserting the tiles two girders are first laid parallel to each other; they are then drawn slightly apart at one end, so as not to be precisely parallel; the tiles are then inserted at the end where the girders are furthest apart and slipped along on the flanges of the girders to their other end, where the girders fit exactly into the slots L in the tile, the edge K' fitting closely up against the girder.

The tiles may have openings, G and E, for ventilation. There may be one or more openings, G, which will appear as in the ceiling of the room below the floor. The air enters the opening and passes through openings E to a flue in the wall. There is no obstruction to the air so passing through the openings E, as each tile is supplied with such openings, and, as they lie side by side, these openings E form a continuous flue in the floor. In case of fire in the room below a great portion of the heat may pass off through these openings G and E. In this case the girder B is prevented from being affected by the heat entering the interior of the tile by the bulk-head or partitions C C; and the top I of the tile, which forms the floor of the room above, is protected from the heat by the partition D, which extends horizontally the length and breadth of the interior of the tile and forms an air-space between itself and the top I of the tile; it also acts as a brace to the partitions C, holding them in place.

These ventilating orifices may be dispensed with, in which case the interior of the tile be-

ing an inclosed air-space there is no danger to the girder B, or the upper part I of the tile, from any heat entering the interior of the tile, and the partitions C C' and D may, therefore, be dispensed with, and the tile will then consist simply of the top I, bottom G, and sides K K', with the slots L and short edge K', Figs. 1 and 2.

Having thus described my invention, what I claim as new, and desire to secure by Letters Patent, is—

1. A fire-proof floor and ceiling tile having flanges M or slots L, or their equivalents, which

cover and protect the girder, joist, or beam, substantially as and for the purpose specified.

2. A fire-proof floor and ceiling tile with orifices for ventilation, and partition D for the purpose specified—viz., to prevent the transmission of heat to the upper part of the tile, or to the floor above—substantially as described.

JAMES BOUNDS.
